CLAIM

The ornamental design for a golf club head, as shown and described.

DESCRIPTION

FIG. 1 is a back heel perspective view of our new golf club head;

FIG. 2 is a heel side view thereof;

FIG. 3 is a toe side view thereof;

FIG. 4 is a back view thereof;

FIG. 5 is a bottom view thereof;

FIG. 6 is a front view thereof; and,

FIG. 7 is a top view thereof.

The broken line showing is included for the purpose of illustrating and forms no part of the claimed design.
